(57) **CLAIM**

The ornamental design for a drying rack, as shown and described.

DESCRIPTION

FIG. 1 is a top perspective view of the design of a drying rack showing the new design and illustrating the drying rack in a folded position;

FIG. 2 is a front elevation view of the drying rack shown in FIG. 1;

FIG. 3 is a rear elevation view of the drying rack shown in FIG. 1;

FIG. 4 is a right side elevation view of the drying rack shown in FIG. 1;

FIG. 5 is a left side elevation view of the drying rack shown in FIG. 1;

FIG. 6 is a top plan view of the drying rack shown in FIG. 1;

FIG. 7 is a bottom plan view of the drying rack shown in FIG. 1;

FIG. 8 is a top perspective view of the drying rack shown in FIG. 1 illustrating the drying rack in a semi-opened position; and,

FIG. 9 is a top perspective view of the drying rack shown in FIG. 1 illustrating the drying rack in a fully-opened position. The broken lines shown in the drawing views are included for the purpose of showing environmental structure that forms no part of the claimed design.
